UNITED STATES PATENT OFFICE.

ANTHONY MATRAZZO, OF BALTIMORE, MARYLAND.

POLISHING DEVICE.

1,405,308.

Specification of Letters Patent.

Patented Jan. 31, 1922.

Application filed March 12, 1921. Serial No. 451,904.

To all whom it may concern:

Be it known that I, ANTHONY MATRAZZO, a subject of the King of Italy, residing at Baltimore, in the State of Maryland, have 5 invented new and useful Improvements in Polishing Devices, of which the following is a specification.

This invention relates to devices for tools especially designed for use in finishing 10 highly polished surfaces, such as automobiles or other vehicles, furniture and the like, the device being susceptible of use for polishing objects of any character.

Another object is the provision of a tool 15 operated polishing device whose use will materially reduce the time and labor of finishing polished surfaces; and to regulate the amount of pressure, in the work, so as to avoid liability of using excessive pressure 20 during the rubbing or polishing operation and thus guard against injury to the finish.

Another object is the provision of a device 25 of the above character which, with minor changes may be used for scrubbing or sand papering and smoothing various surfaces.

With the above and other objects in view, the invention further includes the following 30 novel features and details of construction, to be hereinafter more fully described, illustrated in the accompanying drawings and pointed out in the appended claims.

In the drawings:—

Figure 1 is a vertical longitudinal sectional view of a polishing or rubbing device 35 constructed in accordance with the invention.

Figure 2 is a top plan view with the cover plate removed.

Referring in detail to the drawings, 40 wherein like characters of reference denote corresponding parts, the reference character 10 indicates the body of the device which is preferably rectangular in plan and is of hollow construction. The body is provided 45 with a cover plate 11, which is secured to the body proper by means of fastening devices 12 which pass through apertured flanges 13 extending from above the body to the cover plate. Secured to the cover 50 plate is a handle or grip 14, by means of which the device is held while in use.

The device further includes a movable polishing unit 15, which is secured to the body 10 and is movable relatively thereto. This 55 unit is formed of inner and outer walls 16

and 17, the former being preferably formed of metal or similar non-yieldable material, while the wall 17 is formed of leather or other flexible material and is secured to the wall 16 as shown at 18. The walls 16 and 17 60 are yieldingly held in separated relation by means of coiled springs 19 whose opposite ends engage these walls. The flexible wall 17 is preferably covered with felt or other suitable polishing material 20 so as to provide proper frictional engagement with the surface being polished.

The polishing unit 15 is slidably connected to the body 10 and for this purpose the said body has extending longitudinally 70 of its opposite side walls guide flanges 21, while the inner wall 16 of the polishing unit carries spaced channeled members 22 which receive the guide flanges 21 and hold the polishing unit in sliding engagement with the 75 body of the device. Mounted between ears 23 extending from each of the end walls of the body 10 are anti-friction rollers 24 which bear upon the inner wall 16 of the polishing unit and serve to reduce friction 80 during the operation of the device.

For the purpose of imparting a sliding movement to the polishing unit, the body 10 has rotatably mounted therein a transversely arranged crank shaft 25, the latter being 85 mounted in bearings 26 arranged upon each side of the body 10 and having a connection with the polishing unit 15 through the medium of a pitman. The shaft 25 may be connected to a flexible shaft 27, which may receive power from any suitable source, for example, an electric motor (not shown).

The device is susceptible of various changes, such as substituting a suitable abrasive material for the felt cover 20, 95 whereupon the device may be used as a sandpapering or smoothing device, or a covering of a different character substituted for the felt 20, so that the device may be used for scrubbing or similar work. The right is 100 therefore reserved to make such changes as properly fall within the scope of the appended claim.

Having described the invention what is claimed is:—

A device of the class described comprising a hollow body, a cover plate removably secured to said body, a handle secured to said cover plate, guide flanges extending from the side walls of said body, a polishing unit 110

including a casing having an inner non-yieldable wall and an outer yieldable wall and compressible elements separating the walls, spaced channeled members carried by the non-yieldable wall of the polishing unit and engaging said guide flanges, ears extending from opposite ends of said body, anti-friction rollers carried by said ears and

engaging the non-yieldable wall of said polishing unit, a crank shaft journaled in suitable bearings in said body, means for connecting said shaft to the non-yieldable wall of the polishing unit and means for rotating said shaft.

In testimony whereof I affix my signature. 15
ANTHONY MATRAZZO.
